UNITED STATES PATENT OFFICE.

GERARD BANCKER, OF NEW YORK, N. Y.

BRICK-MACHINE.

Specification of Letters Patent No. 22,694, dated January 25, 1859.

To all whom it may concern:

Be it known that I, GERARD BANCKER, of the city, county, and State of New York, have invented certain new and useful Improvements in Machinery for Making Dry-Pressed Brick; and I do hereby declare the following to be a full description of the same.

The nature of my invention consists in the mode of constructing a dry pressing brick forming machine, by the arrangement and use of a horizontal rotary table, having in it, transversely of its axis, a molding box. In this molding box is arranged two opposing compressors or plungers. These are operated by means of two eccentrics on the vertical axis of the horizontal table, so that as the machine rotates, the brick is firmly pressed on opposite sides, while the upper side is sustained by passing under a semicircular stationary cap plate, secured upon the vertical axis of the machine (and to the upper side of which the hopper is attached); and the lower side by a plunger fitting the lower opening of the mold. This plunger is arranged to work in a suitable box or guides attached to the lower side of the rotating mold box, and at each rotation of it, is elevated by an inclined plane on the base of the machine, so as to lift the brick from the mold when it is transferred to the table by coming in contact with the straight edge of the cap plate as the molding box rotates, thus forming, compressing and discharging the perfectly formed brick by the single rotation of the machine. But to describe my invention more particularly I will refer to the accompanying drawings forming a part of this specification the same letters of reference whenever they occur referring to like parts.

Figure 1, is a plan view of the machine. Fig. 2 is a vertical cut section of the same through the line x, x , Fig. 1. Fig. 3 is a side elevation of the machine. Fig. 4, is a vertical cut section of the end of the machine through the line x^1, x^1 , Fig. 1. Fig. 5, is a detached plan view of the molding box, and plungers or compressors, with operating parts attached thereto. Figs. 6 and 7, side and plan view of the vertical axis of the machine showing the eccentrics attached thereto, for operating the compressors.

Letter A, is the base or tread of the operating parts of the machine. Elevated from the center of this base is a stationary axis

B. Upon this axis is adjusted a horizontal rotatory table C. This table is rotated upon the axis B, by means of a cog wheel D, secured to its base, gearing into a bevel cog wheel E, upon the end of any suitable driving power shaft F, that may be required. Transversely of the axis of the horizontal table board is arranged a brick forming molding box G. This box is formed of any desired size for the brick intended to be made. In it is arranged two compressors or plungers H¹ and H². These are operated by means of two cams, or eccentrics or equivalent device, I¹ and I², secured upon the vertical axis B, and having attached to, and upon them eccentric rods J¹ and J². The rod J¹, is attached to and operates directly upon the compressor H¹. The opposite rod J², is attached to an adjustable plunger K, working in the back end of the molding box, and by means of side connecting rods L, secured by suitable pins l, l, to the ends of the plunger K, and compressor H², causes it to operate simultaneously with the direct action of the plunger or compressor H¹. To the back end of the plunger K, is an adjusting screw M. This screw is secured in the end of the eccentric rod J², and extends back through an opening in the plunger K, so that by means of the nut on it, the plunger K, may be distended outward from the vertical axis, and thereby shorten the throw of the side connecting rods L, to graduate or increase the pressure of the sides of the brick.

Letter N, is a stationary cap plate, adjusted upon the axis B, and fitting closely down upon the upper edges of the molding box, so as to form a covering to the mold, as it rotates, and to sustain the upper edge of the brick from bulging while under the action of the side compressors. Through this cap plate is a feed port n², upon which is adjusted the hopper P, into which the clay is placed for charging the mold as it rotates underneath it. For the purpose of discharging the brick from the mold when formed, a section of the cap plate is cut off, and to prevent it from being warped or springing up under the operation of the compressors, a cleat Q, is secured to the edge of the rotating mold box, which extending over the edge of the cap plate at all times just at the point of action of the compressors holds it firmly down upon the mold box to make a perfectly finished and polished face to the brick as it comes from the machine.

In the lower end of the mold and forming the bottom thereof is a plunger R. This plunger is secured in a vertical guide box S, attached to the lower side of the molding box, so as to rise and fall in the mold as its lower roller end r^2 is carried forward by the rotatory action of the molding box over a cam or inclined plane T, secured upon the upper surface of the base or tread A. The object of this elevating device is to discharge the brick from the mold when formed by elevating it during the intermittent space of the cap plate to a level with the upper surface of the rotating table, upon which it is pushed by coming in contact with its edge, just previous to the mold passing under the hopper to be again charged with clay.

Having now described my invention and its mode of construction I will proceed to set forth what I claim and desire to secure by Letters Patent of the United States. What I claim, therefore, is--

1. The combination of the adjustable plunger K, with the side rods L, and rods j^1 and j^2 , of the rotating mold box, for operating the compressors in the manner described for the purposes specified. 25

2. I also claim the use of the cleat Q in combination with the rotating molding box G, and semi-circular stationary cap plate N, 30 substantially as described and for the purposes hereinbefore set forth.

3. I also claim the use of an elevator plunger R, operating as set forth, in combination with the rectangular rotatory mold box G, 35 adjustable compressors H^1 and H^2 , and cap plate N, as a device for molding and compressing clay into bricks, and discharging the same therefrom.

GERARD BANCKER.
